ELECTRIC STEAM GENERATOR

Kurt Beyrodt, Hartford, Conn., assignor to Electric Steam Sterilizing Company, Inc., New York, N. Y., a corporation of Delaware

Application March 31, 1936, Serial No. 71,883

11 Claims. (Cl. 219—39)

This invention is directed to an improvement in electric steam generators, and has for one of its objects the provision of such an apparatus which will be compact, involve no moving parts, 5 relatively inexpensive to manufacture and of long life.

Generally speaking my invention provides an apparatus in which feedwater is supplied to the top of the apparatus, while the steam outlet may 10 be either at the top or bottom of the apparatus.

My improved apparatus embodies a metal mass 15 into which the heating element is cast, this mass surrounding the evaporating surface, which takes the form of a metal casting extending into the metal mass and provided with a downwardly inclined groove extending helically about the periphery of the casting, means being provided for conducting the generated steam upwardly through the center of the generator to an outlet 20 near the top thereof.

Means are provided adjacent the feedwater inlet for automatic temperature control of the metal mass, this device comprising a thermostat functioning to maintain the metal mass within a 25 predetermined temperature range and to close an electric circuit to the heating element when feedwater is supplied to the apparatus.

I also provide in my improved apparatus for 30 reducing the thermal conductivity of the metal mass adjacent the feedwater inlet, which aids in reducing objectionable bumping and surging when my apparatus is in operation.

In the accompanying drawing:

Fig. 1 is a sectional elevational view of an embodiment of my invention;

Fig. 2 is a plan view;

Fig. 3 is a section on the line 3—3 of Fig. 1; and

Fig. 4 is a sectional elevational view of the 40 temperature control apparatus.

Referring to the drawing in detail, 1 designates a mass of metal, cylindrical, for example, in shape, provided with a groove 2 extending helically of the casting. This metal mass is slightly 45 tapered and is enclosed by a pressure proof metal shell 3 in such a manner that a downwardly extending channel for the fluid to be evaporated is provided. Means are provided for conducting the generated steam upwardly to an outlet near the 50 top of the shell 3 as will be brought out hereinafter.

The top of the shell 3 is provided with a lower wall 4 and upper wall 5 spaced slightly from each other to provide for the flow of water entering the 55 apparatus through inlet 6 before the same enters the evaporating channel above referred to.

These walls are so shaped as to provide a well 60 7 in which is mounted the thermostatic control device shown in Fig. 4 and which will be described in detail hereinafter. By passing the

feedwater between the two walls 4 and 5 the thermostat will be cooled down to insure closing of the electric circuit of the heating element of my generator whenever feedwater is supplied.

The general shape of the shell 3 is cylindrical 5 and tapered and it fits into a hole of the same taper in the heater casting. This heater casting comprises a metal mass 8 into which is cast the heating element 9.

This arrangement provides good contact between 10 all heat conducting parts and insures excellent heat conductivity.

The evaporating surface provided by the arrangement of the grooved casting 1 and shell 3 is in communication with a central channel 10 in 15 the casting to the upper end of which is connected the casting to the upper end of which is connected the steam outlet tubing 11. This tubing is led around the assembled parts for about three quarters of a turn to relieve any stresses set up by temperature changes and is then led to the 20 outside of the apparatus. This tubing is interrupted intermediate its ends for the insertion of pyrex glass tubing 12 to reduce heat losses caused by a continuous copper tubing.

The shell 3, mass 1 and the thermostatic control 25 are held in place by cross member 14 and screws 15.

16 designates a collar slipped over shell 3 before the same is placed in position. This collar is provided with screws 17 and when the same 30 are screwed down collar 16 will be raised to lift shell 3, metal mass 1 and thermostatic control apparatus out of the heater casting 8 for inspection and repair.

At the top of the heater casting I provide a 35 pyrex cylinder or sleeve 18. This sleeve is flared toward its upper end to receive a pyrex container 19 filled with magnesia.

The assembly, i. e., metal mass 1, shell 3 and the heater casting 8, is packed in magnesia 40 or other suitable heat insulation 20 in a vacuum jar 21, the latter being packed in heat insulating material 22 in a sealed casing 23.

It will be seen from the drawing that the feedwater inlet and steam outlet are brought through 45 the top of the casing or container 23.

The leads for the electric heating element are brought from the outside of the apparatus and are designated 24 and 25. One of these leads goes to the heating element direct, the other through 50 fusible link 26 and the thermostat of Fig. 4 to the heating element.

This thermostat, which is a well known commercial article, comprises a disc 27 carrying contacts 28, cooperating with contacts 29 on a bimetallic disc 30. The cold position of this disc is shown in dotted lines in Fig. 4. While this thermostat is set to maintain the heater casting at a predetermined temperature it will be evident that when feedwater is admitted, as above de- 60

scribed, the thermostat will close to close the electric circuit of the heating element.

To reduce the thermal conductivity of the metal mass adjacent the feedwater inlet, I groove the same as shown at 31 and fill this groove with asbestos, magnesia or other suitable heat insulation.

It will be seen from all of the foregoing that I have provided an extremely compact, simple and efficient apparatus for the instantaneous generation of steam. That the apparatus while automatically controlled has no moving parts at all with the exception of the dished bimetal disc 30, and that repairs and renewals are easily made.

15 It is to be understood that changes may be made in the details of construction and arrangement of parts within the purview of my invention.

What I claim is:—

20 1. An electric steam generator comprising in combination a metal mass with a heater cast therein, said mass being provided with a central chamber, a metal shell fitting said chamber, and a second metal mass provided with a grooved 25 periphery fitting within said shell, the said groove in conjunction with said shell providing evaporating surfaces for the generation of steam.

2. An electric steam generator comprising in combination a metal mass with a heater cast 30 therein, said mass being provided with a central chamber, a metal shell fitting said chamber, and a second metal mass provided with a grooved periphery fitting within said shell, the said groove in conjunction with said shell providing evaporating 35 surfaces for the generation of steam, said second metal mass being provided with a central longitudinal passageway for the passage of steam upwardly of the apparatus.

3. An electric steam generator comprising in 40 combination a metal mass with a heater cast therein, said mass being provided with a central chamber, a metal shell fitting said chamber, and a second metal mass provided with a downwardly extending groove on its periphery fitting within 45 said shell, the said groove in conjunction with said shell providing evaporating surfaces for the generation of steam.

4. An electric steam generator comprising in combination a metal mass with a heater cast 50 therein, a metal shell fitting into a chamber in said casting, a second metal mass fitting into said shell, the periphery of said second metal mass being provided with a groove extending helically about its periphery and a feedwater inlet at the 55 upper end of said groove, said shell and second metal mass being removable as a unit from the heater casting.

5. An electric steam generator comprising in combination a metal mass with a heater cast 60 therein, a metal shell fitting into said casting, a second metal mass with a grooved periphery fitting into said shell, a feedwater inlet connected to the upper end of said groove, said second metal mass being provided with a passageway 65 extending from bottom to top of the same, and a steam outlet at the upper end of said passageway.

6. An electric steam generator comprising in combination a metal mass with a heater cast 70 therein, a metal shell fitting into a chamber in said casting, a grooved second metal mass fit-

ting into said shell, a feedwater inlet at the upper end of said groove, and an automatically operable control device adjacent the feedwater inlet for controlling the electric circuit of the heater.

7. An electric steam generator comprising in 5 combination a metal heater casting having a heating element cast therein, a metal shell fitting into said casting, a grooved metal mass fitting into said shell, the groove in said metal mass extending downwardly and in conjunction with 10 said shell providing an evaporating surface, a passageway for steam extending from the bottom to the top of said metal mass, a steam outlet connected to the upper end of said passageway, a thermostat adjacent the upper end of said metal 15 mass for controlling the circuit of said heating element, and metal tubing constituting a feedwater inlet coiled about said casting and connected to the upper end of said groove.

8. An electric steam generator comprising in 20 combination a metal heater casting, a heater element embedded therein, a metal shell fitting into said casting, a metal mass fitting into said shell, the periphery of said metal mass being provided with a helically extending groove co- 25 operating with said shell to provide an evaporating surface, a double walled top for said shell, said walls being spaced apart to provide a passageway for feedwater communicating with said evaporating surface, and a thermostat for controlling the circuit of said heater located immediately above the upper of said walls, whereby admission of feedwater to the apparatus will effect operation of said thermostat to close the 30 circuit of the heater element.

9. An electric steam generator comprising in combination a heater casting, a metal shell fitting into said casting, a metal mass fitting into said shell, said metal mass being provided with a helically extending groove in its periphery, the 40 said groove cooperating with said shell to provide an evaporating surface, said mass being provided with a passageway extending from bottom to top of said metal mass, the lower end of said passageway communicating with said evaporating 45 surface, a thermostat adjacent the upper end of the apparatus and supported thereby for controlling the electric circuit of the heater, said thermostat, metal mass and shell being removable as a unit.

10. An electric steam generator comprising in 50 combination a metal mass with a heater cast therein, said mass being provided with a central chamber, a metal shell fitting said chamber, and a second metal mass provided with a grooved periphery fitting within said shell, the said groove 55 in conjunction with said shell providing evaporating surfaces for the generation of steam, heat insulation for said apparatus and an enclosing vacuum jar.

11. An electric steam generator comprising in 60 combination a metal mass with a heater cast therein, a metal shell fitting into a chamber in said casting, a grooved second metal mass fitting into said shell, a feedwater inlet at the upper end of said groove, an automatically operable 65 control device adjacent the feedwater inlet for controlling the electric circuit of the heater, and a fuse operable to open the circuit of the heater on an excessive temperature rise in the apparatus.

70 KURT BEYRODT.
